UNITED STATES PATENT OFFICE.

JAMES WATSON, OF MARINETTE, WISCONSIN.

ELBOW.

1,333,195.

Specification of Letters Patent.

Patented Mar. 9, 1920.

Application filed December 24, 1917. Serial No. 208,594.

To all whom it may concern:

Be it known that I, JAMES WATSON, a citizen of the United States, residing at Marinette, in the county of Marinette and State 5 of Wisconsin, have invented a new and useful Elbow, of which the following is a specification.

It is the object of this invention to provide a stove pipe elbow which may be folded flat, 10 means being provided for rendering the elbow draft-tight at its joints, and for holding the elbow in condition for use.

It is within the province of the disclosure to improve generally and to enhance the 15 utility of devices of that type to which the present invention appertains.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 25 within the scope of what is claimed, without departing from the spirit of the invention.

In the drawings:—

Figure 1 shows the invention in side elevation, parts being broken away; 30 Fig. 2 is a cross section on the line 2—2 of Fig. 1;

Fig. 3 is a fragmental section taken approximately on the line 3—3 of Fig. 1;

Fig. 4 is a vertical section taken through 35 the parts which form the inner angle of the elbow;

Fig. 5 is a perspective view wherein the elbow is shown folded flat; and

Fig. 6 is a transverse section wherein the 40 pipe is shown folded flat.

The structure forming the subject matter of this application preferably is made of metal throughout. The elbow includes rectangularly disposed members 1 and 2 each 45 of which is rectangular in cross section as Fig. 2 will make manifest, this view being equally applicable to both members of the elbow. The member 1 of the elbow includes an inner wall 3, side walls 4 and an outer wall 5. The member 2 of the elbow includes an inner wall 6, side walls 7 and an outer wall 8. The inner wall 3 is united with the side walls 4 by means of hinges 9, the side walls 4 being united with the outer wall 5 by 55 means of hinges 10. The inner wall 6 of the member 2 is united with the side walls

7 by means of hinges 11, and hinges 12 connect the side walls 7 with the outer wall 8. The hinges above alluded to extend longitudinally of the various walls and preferably are of the usual knuckle and pin construction. The transverse edge of the outer wall 8 of the member 2 is united with the transverse edge of the outer wall 5 of the member 1 by means of a hinge 14. The 60 coöoperating edges of the walls 7 and 4 are mitered as shown at 15. The upper edge of the inner wall 3 of the member 1 is folded downwardly upon itself and is inclined outwardly to form a trough 16 terminating in 65 an upstanding lip 17, these parts extending across the upper edge of the wall 3. The inner wall 6 of the member 2 of the elbow is fashioned into a downwardly inclined tongue 18, received in the trough 16, thus 70 affording a secure closure along the line where the walls 3 and 6 coact. The side walls 4 of the member 1 are folded downwardly and inwardly along the edges 15 to form a trough 19 terminating in an upstanding lip 20. The side walls 7 of the member 2, adjacent the mitered edges 15, are set 75 inwardly as at 21 to form tongues 22 received in the trough 19 and affording tight joints adjacent the edges 15.

In order to hold the parts 1 and 2 of the elbow in the positions shown in Fig. 1, latches are employed, the latches preferably being in the form of hooks 23 pivoted at 24 to the side walls 4 of the member 1, the side walls 7 of the member 2 being provided with eyes 25 wherein the bills of the hooks 23 are received. These eyes, if desired, may be in the form of openings, fashioned in the walls 7. The longitudinal edges of the walls 85 7, 6 and 8 of the member 2 may be left free, adjacent their outer ends, so that the outer terminal portions of the walls may be inset as indicated at 27, to form tongues 26 adapted to be inserted into a section of piping (not shown). The drawings show a pipe which like the elbow, is of rectangular cross section. The pipe 28 comprises walls 29 united by hinges 30, the construction being such that the pipe may be collapsed, as 100 shown in Fig. 6.

In order to collapse the elbow, the hooks 23 are detached from the eyes 25, the member 2 being swung over, on the hinge 14, in the direction of the arrow A in Fig. 1, until 110 the outer wall 8 of the member 2 lies against the outer wall 5 of the member 1. Then,

both of the members 1 and 2 may be collapsed, by pushing them laterally in the same direction, the structure then appearing as shown in Fig. 5, the wall 3 and one 5 of the walls 4 lying flat against the outer wall 5, the other wall 4 extending outwardly from the wall 5 in approximate alinement therewith, and the wall 3 resting against the wall 4, the constituent walls of the member 2 being flattened out in a similar way.

Having thus described the invention, what is claimed is:

A stove pipe elbow comprising angularly disposed members of rectangular cross section having mitered coöperating edges, each member of the elbow including walls; means 15 for hingedly uniting the longitudinal edges

of the walls of each member of the elbow, whereby each member may be folded flat; means for hingedly uniting the members of 20 the elbow along the transverse edges of one wall of each of the members of the elbow whereby said members, having been folded flat, may be folded against each other, the transverse edges of the other walls of the 25 members of the elbow being provided with interengaging elements which afford draft-tight joints; and means for releasably connecting the member of the elbow to hold said elements interengaged.

In testimony that I claim the foregoing as my own, I have hereto affixed my signature.

JAMES WATSON.
